[57] CLAIM

The ornamental design for a bail for a rotary power tiller or the like, as shown and described.

DESCRIPTION

FIG. 1 is a perspective view of a bail for a rotary power tiller or the like, showing my new design, the broken lines showing a rotary tiller are for illustrative purposes only, and form no part of the claimed design;

FIG. 2 is a front elevational view thereof;

FIG. 3 is a side elevational view thereof, the opposite side being a mirror image;

FIG. 4 is a top plan view thereof.

FIG. 1

FIG. 3

FIG. 2

FIG. 4
